STEP-BY-STEP ELECTRIC MOTOR

Willy Lohs, Berlin-Siemensstadt, and Friedrich Sommer, Berlin-Nikolassee, Germany, assignors to Siemens & Halske Aktiengesellschaft, Munich and Berlin, Germany, a corporation of Germany

Application November 30, 1951, Serial No. 259,076
In Germany December 13, 1950

6 Claims. (Cl. 310—49)

1

This invention is concerned with a telephone switching mechanism, and particularly with a motor for driving it.

The particular switching mechanism to which the invention relates is of the class requiring a motor having sets of contacts controlled by the motor armature for alternately switching in the field or stator coils to obtain step-by-step rotation of the motor shaft and thereby corresponding rotation of the switching elements, e. g., of the wipers, of a switching device geared to the motor shaft. An example of such a motor is shown in Patent No. 2,092,546, dated May 28, 1935. The operation of the above mentioned contacts, that is, the closing as well as the opening thereof, must take place in predetermined armature positions. The proper operation of such a mechanism, e. g., of a selector switch, therefore requires an accurate adjustment of the contacts. The adjustment was heretofore carried out by the use of special gages.

The invention eliminates the necessity for special gages by providing for each set of contacts two adjusting members. One of these adjusting members determines the beginning and the other the termination of the contact operation through the medium of a cam on the motor shaft. The adjustment of the corresponding contact set by the second adjusting member does not alter the functions of the contact position determined by the first adjusting member.

The motor armature is provided with an adjusting disk having a plurality of straight edges, and a stationary motor part forms a straight coacting adjusting surface. The adjustment of the contacts is carried out by holding the motor shaft and therewith the armature and a contact-actuating cam on the motor shaft in definite angular positions, by inserting between the straight edges of the adjusting disk and the coacting stationary adjusting surface a wedge-shaped member for holding the armature against rotation in the critical angular position thereof in which the cam is in definite position relative to the contacts controlled thereby.

The adjusting disk on the motor shaft is also employed for determining the armature positions in which the wipers of the switch controlled by the motor are in predetermined resting or operating positions, respectively. This is done by placing the motor armature in a certain angular position in which a detent spring engages a notch in a detent ratchet to hold the armature in the angular position corresponding to the desired operating positions of the switch wipers. The correct position of the detent spring relative to the detent ratchet is adjusted after determining the correct angular position of the armature. This phase of the adjustment operations therefore also is accomplished without the use of special gages.

2

The invention is illustrated in the accompanying drawings, in which

Fig. 1 is a view, partly in elevation and partly in section, of the parts of the drive motor for a switch of the type mentioned before, which are required for the understanding of the invention;

Fig. 2 is a side view with certain parts in section;

Figs. 3-6 show details in elevational and sectional views, respectively; and

Fig. 7 illustrates a circuit.

The parts shown in Figs. 3-5 are on a somewhat smaller scale than they appear in Figs. 1, 2 and 6.

Numeral 1 indicates parts of the stationary mounting frame, which is made of nonmagnetic material. On this frame are fastened the core members 2 and 3 of the field or stator coils of the motor. The frame 1 also carries the bearing 20 for the armature shaft 4. One such bearing is indicated in Fig. 2. Also mounted on the frame 1 are the carriers for the control contacts 7 and 8 which are governed by the cam disk 6. These contacts govern the alternate switching in and out of the field or stator coils coacting with the cores 2 and 3. Numeral 9 (Fig. 6) is a cam portion which opens the normally closed contacts 7 and 8 incident to passing between the corresponding contact springs. The two positions of this cam portion are indicated at I and II.

Disposed on the armature shaft 4 is the pinion 11 which meshes with the drive wheel (not shown) of the associated switch, for example, a selector switch. The switch has been omitted

35 from the drawings to keep them simple. Also disposed on the shaft 4 are the detent ratchet 12 and four stacks of armature laminations 13 which are separated by spacers 14 and 15. Finally, the shaft 4 also carries the cam disk 6 for operating the contacts 7 and 8. The spacer 15 between the second and third laminated armature stacks is a pentagonal disk having five straight sides or edges 30-34. These edges are provided for coaction with the wedge-shaped holder member 28 (Fig. 1) to carry out the various ad-

30 justments in definite angular positions of the armature. The edge 30 serves for holding the armature in the angular position which it must assume in normal position and in working position, respectively, of the switch wipers. The edges 31-34 are employed in the adjustment of the contacts 7 and 8 which control the field or stator coils. The various disks, armature laminations, spacers and the cam are held axially against the pinion 11, which is press-fitted on the shaft 4, by the nut 40 16. The various elements are keyed to the shaft 4 by engagement of recessed portions with a flattened surface on the shaft and are thus held against rotation.

Each contact pair 7 and 8 is mounted on a car-

rier which is formed by an adjusting lever or member provided with a handle. The pair of contact springs 7 is thus mounted on the carrier forming the lever having the handle 17, and the pair of contact springs 8 is similarly mounted on the carrier forming the leverlike adjusting member having the handle 18. The adjusting lever 17 is pivotally mounted at 20 on the platelike adjusting member 19 and may be secured in adjusted position by means of the screw 21. The adjusting lever 18 is similarly pivotally mounted on the coacting platelike adjusting member 22 at 23 and may be secured in position by the screw 24. The platelike adjusting members 19 and 22 are rotatably mounted on the bearing 5; that is, they are angularly, rotatably adjustable concentric to the axis of shaft 4. These platelike adjusting members 19 and 22 may be secured in adjusted position by the screws 25, 26 and 27.

The plate member 19, which overlies the adjusting lever 17, is shown in Fig. 5 broken away in order to illustrate the shape of the adjusting lever 17 and the manner in which it is rotatable about the pivot 20. The adjusting lever 18 carrying the contacts 8 is similarly formed and coacts in a similar manner with its associated platelike adjusting member 22.

In order to adjust the contacts, the screws 21 and 24 are first tightened so as to connect or couple together the adjusting levers 17 and 18 with the respective coacting platelike adjusting members 19 and 22. With the screws 25, 26 and 27 loosened, the contact set 8 can now be pivotally moved about the journal 5 by means of the lever 18, since the platelike adjusting member 22 has been clutched to or coupled with the lever 18 by the screw 24. The contact set 8 is rotated clockwise to a position in which the cam 9 of the disk 6 is in the position I in which it begins to open the springs forming the contact set 8. The platelike adjusting member 22 is then in the adjusted position secured on the motor frame by tightening the screw 25 which has its head in a recess 32 in the platelike adjusting member 19.

The armature and therewith the cam disk 6 are held during this adjusting operation in an angular position in which the cam part 9 is in the position I. This holding operation is accomplished by the insertion of the wedge-shaped holding member 28 in coaction with one of the straight edges of the disk 15.

The motor armature must also assume a definite angular position in the normal and in the resting positions of the switching mechanism operated by the motor. In this position, and as shown in Fig. 2, the cam 9 of the disk 6 has opened the contact 8 (see also Fig. 7). Contact 7 is closed. Contact an will be closed to complete a circuit for the stator coil M1 (Figs. 3 and 7) so as to start the motor. The armature now rotates and contact 8 will be closed so as to switch in the stator coil M2. Contact 7 is thereupon opened. Incident to further rotation the contact 7 will be closed to switch in the stator coil M1 and the contact 8 will be opened to disconnect the coil M2. This interplay continues. The resting or normal position of the motor armature is determined by placing the armature and therewith the adjusting disk 15 into the angular position shown in Fig. 1. The adjusting edge 30 of the disk 15 is in this position parallel to the axis of symmetry of the field or stator coils, which bisects the angle formed by the axes 2' and 3'. The adjusting edge 30 may, however, extend differently relative to the axis of symmetry; for

example, it may extend at right angles thereto. The armature is held in this angular adjusting position by inserting the wedge-shaped holder member 28 between the adjusting edge 30 and the straight backing surface 29 formed on the motor frame 1. The detent spring 35 is adjustably mounted on the frame 1 and such spring is now manipulated into engagement with the notch 36 on the detent ratchet 12, and is then secured in this position on the motor frame. It is understood of course that the backing surface 29 may be provided on a different part, for example, on an extension of a magnet core such as the core 3.

If the adjusting edge 30 of the disk 15 is positioned to extend in a plane parallel to or perpendicular to the axis of symmetry of the stator coils, which bisects the angle formed by the axes 2' and 3', as described, it is possible to change the direction of rotation (right or left hand rotation) of the motor without altering the determined armature position, simply by loosening the nut 16 and displacing the laminated armature stacks with their spacers by ninety degrees. The correct angular operating position of the armature results from the angular position of the detent 35, which remains unaltered irrespective of the angular positions of the laminated armature stacks for either direction of rotation.

The angular armature positions in which the contacts 7 and 8 have to be respectively opened and closed do not correspond with the position of the armature, which has been determined by the aid of the adjusting edge 30 of the disk 15. The reason resides in the fact that the stator coil, which is in circuit at the beginning of a switching step of the mechanism, is disconnected after one half-step subsequent to the switching in of the other stator coil. During the second half-step takes place the disconnection of the second stator coil subsequent to the re-connection of the first stator coil, leaving this coil alone in circuit at the beginning of the next step of the switch.

The adjusting edges 31—34 are provided on the disk 15 in order to hold the armature in the positions in which the two contacts 7 and 8 are opened and closed by the cams on the cam disk 6.

The cam 9 (Fig. 6) is, for example, in position I at the time when the armature is angularly positioned, so that one of the edges 31—34 assumes the position in which the edge 30 is shown in Fig. 1. The armature is then held by inserting the wedgelike holding member 28, and the adjusting lever and contact carrier 18 is adjusted as described before.

In order to place the cam 9 into the position II, the holder member 28 is removed and the armature is rotated until another edge of the disk 15 is in position for the described coaction with the holder member 28.

The screw 24 is loosened, and the contact carrier having the adjusting lever 18 can then be rotated about the pivot point 23. This pivot point is placed so that, incident to the angular displacement of the lever 18, the point of contact at the contact springs will move nearly in parallel with the edge of the cam when the cam is in position I. The adjustment of the contact 8 obtained in the cam position I is thus maintained during its adjustment in the cam position II. The lever 18 and therewith the contact set 8 are now rotated counterclockwise until the cam begins to separate the contact springs. The lever 18 carrying the contacts 8 is then secured in adjusted position by tightening the screw 24.

The contacts 8 are now adjusted so that they always open and close at the proper moments during the operation of the switch controlled by the motor.

The adjustment of the contacts 7 takes place in two other positions of the armature and of the cam 9, which are again determined by means of the angular positions of the adjusting disk 15 in cooperation with the wedge-shaped holder 28. In the first of these two armature positions, the cam 9 assumes the position relative to the contact 7 which corresponds to the position I incident to the adjustment of the contacts 8. The adjustment carried out by the displacement of the platelike adjusting member 19, which is coupled with or clutched to the adjusting lever 17, is secured by the screw 21, thereby connecting the platelike adjusting member 19 with the platelike adjusting member 22 which is secured on the motor frame 1 by the screw 25. This latter screw does not impede the adjustment of the platelike adjusting member 19 due to the recess 32 formed therein. The second adjustment of the contacts 7 is then carried out, after loosening the screw 21, in a further position of the cam 9 which corresponds to the position II, and such adjustment is secured by tightening the screws 21 and 26.

We claim:

1. A telephone switching device of the class described comprising a drive motor, said drive motor comprising a stationary frame, a shaft journaled in said frame, said shaft carrying a control cam and an armature, a plurality of coil-carrying cores on said frame for magnetic coaction with said armature to rotate said shaft, a plurality of contact sets operable by said cam responsive to rotation thereof for governing the actuation of said coils, and a device for adjusting the positions of said contact sets relative to the angular positions of said control cam to bring about actuation of said contact sets in predetermined angular positions of said armature, said device comprising a carrier for each contact set, a mounting member for each contact set, means for pivotally mounting each carrier on its associated mounting member, means for pivotally mounting said mounting members on a common axis, a polygonal adjusting disk carried on said motor shaft, said disk forming a plurality of straight edges, a straight backing surface formed on a stationary motor part, and a holder member for insertion between any one of the straight edges formed by said adjusting disk and said stationary surface to hold the motor shaft and associated parts including said cam and said armature in predetermined angular position for subsequent angular displacement of the respective carrier and mounting members of said contact sets to adjust said contact sets for predetermined actuation by said cam.

2. The structure defined in claim 1, together with a detent ratchet on said motor shaft which is rotatable therewith, a detent spring for cooperation with said detent ratchet and means for adjustably mounting said detent spring, one of said straight edges on said polygonal adjusting device determining responsive to insertion of said holder member the angular position of said armature which corresponds to a predetermined operating position of the switching device controlled by said drive motor, and means for adjusting in this angular position of said armature said detent spring for coaction with said detent ratchet.

3. In a telephone switch of the class described having a motor including a shaft carrying an armature which is rotatable responsive to energization of associated stator coils in circuits including two control contacts, one control contact for the circuit of each stator coil, a device for adjusting the angular positions of said control contacts relative to said armature to secure proper operation of said stator coils, said device comprising a control cam disposed on said shaft for governing the actuation of said contacts in different angular positions of said armature, a pair of adjusting members for each of said contacts, means for successively holding said armature in two successive predetermined angular positions, means for angularly adjusting in one of said positions of said armature concentrically with respect to the axis of said shaft a first one of the adjusting members of one of said pair of adjusting members associated with one of said control contacts to place such contact into an angular position in which actuation thereof can be started by said control cam and fixing such adjusted position of said first adjusting member, and means for thereafter angularly adjusting in the other held position of said armature a second one of said adjusting members associated with the same contact eccentrically with respect to the axis of said shaft to place such contact into an angular position in which operation thereof by said control cam is completed without altering the position of said contact effected by the adjustment of said first adjusting member.

4. The structure defined in claim 3, comprising means for rotatably mounting said second adjusting member on said first adjusting member, and means for fixing said second adjusting member in the adjusted position.

5. The structure defined in claim 3, comprising means for mounting the associated contact on said second adjusting member, means for rotatably mounting said second adjusting member on said first adjusting member, means for securing said second adjusting member in adjusted position on said first adjusting member, and a handle for said second adjusting member to carry out adjustment thereof and also adjustment of said first adjusting member.

6. The structure defined in claim 3, wherein said means for holding said armature in predetermined positions comprises a polygonal disk having a plurality of straight edges mounted on said motor shaft and rotatable therewith, a fixed member forming a straight backing surface, and a wedge-shaped auxiliary removable member for insertion in engagement with said straight surface and selectively with one of said straight edges.
